UNITED STATES PATENT OFFICE

JULES LINDAUER, OF PARIS, FRANCE

BREAST SUPPORTER, CORSELET, CORSET, AND THE LIKE

Application filed February 17, 1928, Serial No. 254,993, and in France April 5, 1927.

The present invention relates to improvements in breast supporters, corsets and like articles, characterized in that the said articles are strengthened at the front part by applied pieces which are secured by stitching. The said pieces have a pointed shape, and their upper point is situated below the nipple of the breast; said applied pieces are attached between the edges which give a convex or bulged shape to the front part of the cloth of the breast supporter, and they extend upon the front of the breasts, whereby the latter are effectively supported and are held in the raised position.

15 My said invention further relates to a method for making and for securing the said applied pieces. Each applied piece thus consists of a piece of cloth which is secured to the fabric of the breast supporter (or the like) or is formed in one with the said fabric; said applied piece is folded upon itself along a middle line, and its edges are placed together and are sewed upon the corresponding edges of the breast supporter, the same being preferably consolidated by cross stitching at a suitable distance below the said pointed part of the breast supporter.

20 The following description with reference to the appended drawings which are given by way of example shows various embodiments of the invention.

25 Figs. 1, 2, 3 and 4 show the successive stages of the manufacture of a breast supporter according to the invention, by the use of a piece of textile fabric forming part of the cloth of the breast supporter.

30 Figs. 5, 6 and 7 show these successive stages when the applied piece is mounted upon the fabric.

35 Fig. 8 is a general view of a breast supporter, as shown in the preceding figures, when placed upon the wearer.

40 In the example shown in the drawings, the front fabric of the breast supporter is preliminarily given the shape which is represented in Fig. 1. Upon this piece are drawn two lines $o-a$ and $o-b$ on the respective sides of the middle line $o-m$. The vertex

nipple of the breast, when the completed device is placed in position.

45 The part of the cloth in the angle $o-a-b$ is folded on the middle line $o-m$ (Figs. 2 and 3) so that the lines $o-a$ and $o-b$ will be matched upon their whole length. The two parts of the cloth thus folded together are connected by stitching along the common line $o-a-o-b$, and when thus united they form the applied piece of the breast supporter. This assembling line $o-a-o-b$ gives the proper convex shape to the front part of the device, while at the same time it constitutes one of the lines for securing the said applied piece.

55 The said applied piece is then folded down upon the common line $o-a-o-b$ against the cloth of the breast supporter (Fig. 3), and is held by stitches along the outline $m-o-a-c$ of the said applied piece and by cross stitches such as $a-q$ situated at the proper distance below the point o . The said point may be flattened or blunted by turning it down according to a small corner portion, and by sewing it to the front or back of the breast supporter, as shown in Fig. 4.

60 By this means, the front part of the said supporter, strengthened by the said applied piece, will fit upon the breast and will effectively support it at the front part as far as the nipple, holding it up as shown in Fig. 8.

65 The complete device consists of two like parts which are symmetrical with reference to the middle line $g-h$ and are assembled according to said middle line, each part being strengthened by an applied piece of the kind described.

70 In Fig. 3, the applied piece is sewed to the outside of the breast supporter.

75 This disposition may be inverted, as shown in Fig. 4, by turning the front part of the said supporter inside out, without any change in the general shape of the part fitting upon the breast. The assembling of the two like parts forming the breast supporter is effected in the same conditions.

80 When preliminarily shaping the cloth, it may be cut at $o-a$ and $o-b$ and may be placed upon a piece of cloth which when in place will have the same outline $o-a-c$.

d-b-o, as shown in Figs. 5, 6 and 7. Herein the fabric of the applied piece and the fabric of the front part of the breast supporter are preliminarily cut according to suitable outlines as shown in Fig. 5; the vertex *o* is so disposed that it will come below the nipple when the complete device is worn. As in the preceding example, the part of the cloth which forms the applied piece is then 10 folded on the middle line *o'-m*, and the edges *o'-a'*, *o'-b'* of the applied piece and the edges *o-a* and *o-b* of the breast supporter are connected by stitches, as shown in Figs. 6 and 7. The applied piece thus secured 15 in place is folded down upon the lower part of said supporter as before, and the stitching *o-m-c-a* holds the folded applied piece against the cloth of the breast supporter; it may be further strengthened by cross stitching such as *a-q* situated below the breast.

Obviously, the invention is not limited to the form of construction herein specified. Various devices may be provided with applied pieces similar to the ones described 25 and obtained by like means, such devices comprising corselets, belts, one-piece dress bodies, combined corsets and breast supporters, and the like; each half of the article may be made of one or more pieces, according to common 30 practice; said articles may be closed by buttons, clasps, lacing, or like means, which may be placed at the back or other suitable part of the bust or waist according to the current practice. The said articles may consist of 35 the current textile fabrics, such as woven bands, knitted goods, tulle, elastic fabric, or a combination of several fabrics.

Having now described my invention, what I claim as new and desire to secure by Letters 40 Patent is:

1. In each one of the two symmetrically disposed halves of a bust supporting garment joined together by stitching on their front edges which fit into the vertical front center line of the bust between the two breasts, a reinforcing piece of fabric having an outline with at least three adjacent sides, a first side being attached along a part of said front edge of the corresponding half of the garment and two other sides forming an angle, the apex of which is placed directly below the nipple of the breast, one side of said angle being attached on said garment along a substantially horizontal line ending at said first side, and the other side of said angle being attached on said garment along a line extending towards the lower part of said garment.

2. In each one of the two symmetrically disposed halves of a bust supporting garment joined together by stitching on their front edges which fit into the vertical front center line of the bust between the two breasts, a reinforcing piece of folded fabric having an outline with at least three adjacent sides, a first side being attached along a part

of said front edge of the corresponding half of the garment and two other sides forming an angle, the apex of which is placed directly below the nipple of the breast, one side of said angle being attached on said garment along a substantially horizontal line ending at said first side, and the other side of said angle being attached on said garment along a line extending towards the lower part of said garment.

3. In each one of the two symmetrically disposed halves of a bust supporting garment joined together by stitching on their front edges which fit into the vertical front center line of the bust between the two breasts, a dart in said half garment extending substantially along a horizontal line from below the nipple of the breast to said vertical front edge, and a reinforcing piece of fabric having an outline with at least three adjacent sides, a first side being attached below said dart along a part of said front edge of the corresponding half of the garment, and two other sides forming an angle, one side of said angle being attached on said garment along said dart and the other side of said angle being attached on said garment along a line extending towards the lower part of said garment.

4. In each one of the two symmetrically disposed halves of a bust supporting garment joined together by stitching on their front edges which fit into the vertical front center line of the bust between the two breasts, a dart in said half garment extending substantially along a horizontal line from below the nipple of the breast to said vertical front edge, the symmetrically folded fabric of said garment comprised between the two edges of said dart having an outline with at least three adjacent sides, a first side being attached below said dart along a part of said front edge of the corresponding half of the garment, and two other sides forming an angle, one side of said angle being attached on said garment along said dart and the other side of said angle being attached on said garment along a line extending towards the lower part of said garment.

5. In each one of the two symmetrically disposed halves of a bust supporting garment joined together by stitching on their front edges which fit into the vertical front center line of the bust between the two breasts, the lower edge of said garment being adapted to be applied on a part of the waist, a quadrangular reinforcing piece of fabric having a first side attached along a part of said front edge of the corresponding half of the garment, a second side attached along a part of the lower edge of the garment and two other sides forming an angle, the apex of which is placed directly below the nipple of the breast, one side of said angle being attached on said garment along a substantially

horizontal line ending at said first side, and the other side of said angle being attached on said garment along a line ending at said lower edge of said garment.

- 5 6. In each one of the two symmetrically disposed halves of a bust supporting garment joined together by stitching on their front edges which fit into the vertical front center line of the bust between the two breasts, a
- 10 10 reinforcing piece of fabric having an outline with at least three adjacent sides, a first side being attached along a part of said front edge of the corresponding half of the garment and two other sides forming an angle,
- 15 15 the apex of which is placed directly below the nipple of the breast, one side of said angle being attached on said garment along a substantially horizontal line ending at said first side, and the other side of said angle being
- 20 20 attached on said garment along a line extending towards the lower part of said garment, transverse stitchings joining the reinforcing piece and the garment, and extending from an intermediate point of said line
- 25 25 extending towards the lower part of said garment to a point of one of the other sides of said reinforcing piece.

In testimony whereof I have signed my name to this specification.

30 JULES LINDAUER.
